DESIGN.

—o—
L. TULLY.

MISS'S COSTUME.

No. 15,690.

Patented Jan. 6, 1885.

UNITED STATES PATENT OFFICE.

LOUISE TULLY, OF NEW YORK, N. Y., ASSIGNOR TO THE BUTTERICK PUBLISHING COMPANY, (LIMITED,) OF SAME PLACE.

DESIGN FOR A MISS'S COSTUME.

SPECIFICATION forming part of Design No. 15,690, dated January 6, 1885.

Application filed November 22, 1884. Term of patent 3½ years.

To all whom it may concern:

Be it known that I, LOUISE TULLY, of the city, county, and State of New York, have invented and produced a new and original Design for a Pattern of a Miss's Costume, (numbered 9,515;) and I do hereby declare that the engraved prints accompanying this specification convey to any one accustomed to using paper patterns a clear understanding of how 10 a garment made up by the pattern will appear.

The design shows a round walking-skirt and an overdress. The skirt exhibits a front drapery that shapes a deep point at the right- 15 side end, is short and round at the left side, and displays draping plaits in its back edges and just above the front edge of the pointed portion. The overdress exhibits closely-fitted

basque-fronts slightly pointed at the bottom and displaying a closing all the way down, a 20 closely-fitted polonaise back falling in square outline nearly to the bottom of the skirt and displaying under-folded plaits at the lower ends of its middle three seams, draping plaits high up in its front edges, and loopings at the 25 center and at each side, coat sleeves, and a standing collar.

What I claim as my invention, and desire to secure by Letters Patent, is—

The design for a miss's costume, as shown 30 in the engraved prints accompanying this specification.

LOUISE TULLY.
